UNITED STATES PATENT OFFICE

2,137,641

TERMINAL RECEPTACLE FOR GAS RANGE
OVEN LIGHTSJoseph Beevar, Wickliffe, Ohio, assignor to The
Cleveland Cooperative Stove Company, Cleve-
land, Ohio, a corporation of Ohio

Application February 23, 1937, Serial No. 126,981

5 Claims. (Cl. 240—5)

This invention relates to a terminal receptacle for lighting and electrical fixtures on gas ranges and the like and particularly to a new and improved mounting for an oven light such as described in United States Letters Patent, No. 1,992,209, issued February 26, 1935.

As therein more fully described, it is necessary in oven light structures of this character, that the bulb shank and electric socket be exposed to the outside air in a manner such that there is free circulation of air thereabout to cool the bulb and socket and prevent heating of the bulb shank and socket to a dangerous degree. In order to obtain adequate ventilation and cooling, it is necessary to mount the socket entirely outside of the oven compartment with the bulb so arranged with respect to the socket and oven compartment as to light the interior of the oven through an aperture in its rear wall.

Underwriting and electrical laboratories, however, require that electrical connections to all such fixtures must be fully enclosed and protected so that the operator will not be in danger of electrical shock by contact therewith or short circuited currents therefrom.

In addition to the oven light above described, it has become customary practice to provide illuminating lights for the tops of the ranges and also electrical electrical clocks, and other electrical fixtures.

One of the principal objects of the present invention is to provide a combined terminal receptacle and mounting for supporting and supplying current to an oven light in such manner that the electrical connections are entirely enclosed and protected and are maintained in relatively cool condition by circulation of air thereabout.

A correlative object is to provide a terminal receptacle for this purpose in which suitable plug sockets are provided for connection to other electrical apparatus utilized in connection with the range.

Still another object is to provide a terminal receptacle which is mounted so that the fixtures thereof may be rendered accessible readily to the operator to permit the bulb to be changed in the usual manner without danger of short circuiting against the metal of the range or in any other manner during the installation or removal thereof.

Other objects and advantages will become apparent from the following specification wherein reference is made to the drawings, in which:

Fig. 1 is an end elevation of the range with a

terminal receptacle embodying the principles of the present invention attached thereto;

Fig. 2 is a fragmentary rear elevation of the range and terminal receptacle illustrated in Fig. 1;

Fig. 3 is an enlarged fragmentary rear elevation of a portion of the range showing the terminal receptacle and cooperating parts connected thereto, part of the receptacle being shown in section;

Fig. 4 is a vertical sectional view taken on a plane indicated by the line 4—4 in Fig. 3; and

Figs. 5 and 6 are horizontal sectional views taken on planes indicated by the lines 5—5 and 6—6, respectively, in Fig. 4.

Referring to the drawings, the present invention is shown as installed on a range 1, having an oven compartment 2 which is closed at the front by a suitable downwardly swinging door 3. The range also carries a suitable splash panel or rear guard 4 on which an electric light 5 is mounted in position for illuminating the top of the range. An electrically operated clock 6 is mounted on the splash panel 4 at the range in the usual manner. The top or service burners of the range 20 are covered by the usual coverall 7 which is connected at its rear edge by double hinges 8 to a downwardly sliding carrier 9. The carrier 9 is slidably mounted on suitable guides 10 on the rear wall of the range so that the coverall 7 may be lifted to an upright position and dropped behind the range. A suitable opening 11 is provided in the rear panel of the range to accommodate passage of the coverall 7. In addition, the top wall or panel 12 of the range is secured at its rear edge to the range by a suitable hinge 13 so that the entire top panel 12 may be lifted to a vertical position to permit access to the service burners for cleaning and repairs.

In the range in connection with which the present invention is illustrated, the oven has a rear wall 15 in which is a suitable aperture 16, a metal liner or sleeve 17 being provided to line the aperture. The liner 17 is provided at its inner end with a slightly inturned peripheral flange 18 which defines an annular abutment which is preferably slightly less in diameter than the bulb to be associated with the aperture so that the bulb may be seated from the outside against the flange 18 and thus protrude slightly into the interior of the oven but without danger of passing entirely thereinto. Mounted on the rear wall of the oven is one arm 20 of a suitable hinge, the other arm 21 of which extends normally a predetermined distance from the rear 55.

of the range. Mounted on the arm 21 in spaced relation to the rear wall of the range is a terminal receptacle 22. As illustrated, the receptacle 22 preferably is comprised of imperforate sheet metal and is provided intermediate its ends with a sub-compartment 23 in which are carried the usual sockets 24 for receiving saber connections. Below the compartment 23 in the box 22 is a push button switch 25 which is rigidly mounted in the box and has the usual push button 26 extending outwardly therefrom towards the rear wall of the oven.

Mounted within the receptacle at the upper or opposite end thereof is a light socket 28, the light socket being fixedly secured to the front wall of the receptacle 22 and extending forwardly thereof so as to be accessible from the front thereof. Carried in the socket 28 is a bulb 29 which, when the receptacle is in an upright position, seats against the flange 18 of the liner 17. The receptacle 22 is held in upright position by a suitable tension spring 30 connected at its ends to the rear wall of the oven, as illustrated, and looped around the receptacle. The force of the spring 30 is resisted entirely by the bulb 29 engaging the flange 18. Suitable lead-in wires 33 extend through an opening in the bottom wall of the receptacle 22, and are protected within the receptacle opening by a suitable cushion 34 so as to eliminate any danger of abrasion of the lead-in wires by the edges of the opening. In order to protect the socket and other connections within the box from any pull occasioned by pulling the wires 33, the lead-in wires are knotted, as at 35, in the box, thus providing a suitable anchor. The sockets 24 are connected in parallel to the lead-in wires 33. The switch 25, on the other hand, is connected in series with the socket 28 and with the lead-in wires 33. The switch is so positioned that the button 26 is movable horizontally fore and aft of the range just above the floor of the oven.

An operating rod 38, carried by the range, extends from the button 26 to the front of the range in position to be engaged by the door 3. The switch is arranged to complete the circuit to the light when the door is in open position and to break the circuit through the medium of the rod 38 when the door is moved to closed position. For this purpose the outer end of the rod adjacent the front of the range is positioned in such manner as to be engaged by the door 3 itself upon lifting thereof to closed position.

Carried on the arm 21 is a suitable stop 39 which, when the receptacle 22 is swung outwardly from the rear oven wall, as indicated in the dotted lines in Fig. 4, engages the rear wall of the oven and stops the receptacle substantially in this position so that it is easily accessible to the operator.

Suitable lead wires 40 and 41 lead to the light 5 and clock 6 respectively, these wires being provided with the usual saber plug-in connections for engagement with the sockets 24 respectively. It will be seen that the socket 28 and the shank 65 of the bulb 29 are positioned entirely in the open behind the oven wall and out of contact therewith so as to be ventilated freely and thus prevented from reaching a temperature which might be dangerous to the bulb or socket. Furthermore 70 there is no metal to metal conduction of heat from the range into the socket and bulb shank. The same is true as to the plug-in sockets 24 and switch 25. In addition, all incidental electrical connections are entirely protected both from the 75 heat of the oven and from exposure to the opera-

tor and all parts are so arranged that there is no dangerous flexure of any wire or connection during opening and closing of the receptacle 22.

Having thus described my invention, I claim:

1. In a range having an oven compartment with a rear wall having an aperture therein and a door for said compartment, a closed receptacle, hinge means connecting the receptacle to the rear wall of the oven and supporting the receptacle in rearwardly spaced relation therefrom, a socket carried by said receptacle in rearwardly spaced relation from the oven wall, an electric bulb carried in said socket and extending forwardly therefrom and seated in said aperture when the receptacle is in one position, a switch carried by the receptacle and having an operating button extending forwardly therefrom, electrical connections between the switch and the socket within the receptacle and lead wires connected in said circuit and extending through a wall of said receptacle and being arranged for connection to a source of current, operating means carried by the range and operative consequent upon movement of the door to open position to cause actuation of the switch for lighting the bulb, and operable upon moving of said door to closed position for breaking the circuit to said bulb.

2. In a range having an oven compartment with a rear wall and an aperture in said rear wall, a terminal receptacle, hinge means connecting the receptacle to the rear wall of the oven and supporting the receptacle in rearwardly spaced relation therefrom, a socket carried by said receptacle and spaced rearwardly from the oven wall, an electric bulb carried in said socket and extending forwardly therefrom and seating in said aperture when the receptacle is in operating position, switch means, electrical connections between the switch means and the socket, lead wires connected in a circuit with the switch means and socket, and means yieldably urging said receptacle into a position to hold the bulb seated in said aperture with the socket and shank of the bulb exposed in spaced relation to the rear wall of the oven.

3. In a range having an oven compartment with a door therefor and with a rear wall having an aperture therein, a closed receptacle, hinge means connecting the receptacle to the rear wall of the oven and supporting the receptacle in rearwardly spaced relation therefrom, a socket carried by said receptacle and spaced rearwardly from the oven wall, an electric bulb carried in said socket and extending forwardly therefrom and seated in said aperture when the receptacle is in one position, a switch carried in the receptacle and having an operating button extending forwardly therefrom, electrical connections between the switch and the socket, lead wires connected in a circuit with the switch and socket and extending through a wall of the box, anchor means for arresting outward movement of the wires from the box and relieving stress on the connections therein, said lead wires being arranged for connection to a source of current, operating means carried by the range and operative consequent upon movement of the door to open position to actuate the switch for lighting the bulb, and operable upon moving of said door to closed position for breaking the circuit to said bulb, and means yieldably urging said receptacle into a position to dispose the bulb in said aperture with the bulb socket and shank of the bulb exposed in spaced relation to the rear wall of the oven.

4. In a range having an oven compartment with a rear wall and an aperture in said rear wall, a closed receptacle, hinge means connecting the receptacle to the rear wall of the oven and supporting the receptacle in rearwardly spaced relation therefrom, a socket carried by said receptacle and spaced rearwardly from the oven wall, an electric bulb carried in said socket and extending forwardly therefrom and seated in 10 said aperture when the receptacle is in one position, a switch means, electrical connections between the switch means and the socket, lead wires connected in a circuit with the switch and socket and arranged for connection to a source of current, operating means carried by the range and operative consequent upon movement of the door to open position to actuate the switch means for lighting the bulb, and operable upon moving of 15 said door to closed position for breaking the circuit to said bulb, means yieldably urging said receptacle into a position to dispose the bulb in seated relation in said aperture with the socket and shank of the bulb exposed in spaced relation to the rear wall of the oven, and said receptacle being movable to a different position more rearwardly from the rear wall of the oven and affording ready access to the bulb and socket. 20
5. In a range having an oven compartment with a door therefor and with a rear wall having an aperture therein, a closed receptacle, hinge means at the lower edge of the receptacle connecting the receptacle to the rear wall of the oven and normally supporting the receptacle in upright position with its front wall in rearwardly spaced relation from the rear oven wall, a socket carried by said receptacle and extending through 5 said front wall and terminating in rearwardly spaced relation from the rear wall, an electric bulb carried in said socket extending forwardly therefrom and seated in said aperture when the receptacle is substantially upright, a switch carried by the receptacle and having an operating button extending forwardly therefrom through said front wall, electrical connections between the switch and the socket, a lead wire connected in said circuit and extending through a wall of 15 the box, anchor means for arresting outward movement of the wires from the box and relieving stress on the connections therein, said lead wire being arranged for connection to a source of current, operating means carried by the range 20 and operative consequent upon movement of the door to open position to actuate the switch for lighting the bulb, and operable upon moving of said door to closed position for breaking the circuit to said bulb, and means yieldably urging 25 said receptacle into upright position to seat the bulb in said aperture with the socket and shank of the bulb exposed in spaced relation to the rear wall of the oven.
